UNITED STATES PATENT OFFICE.

GEOEGE H. EYER AND ELWOOD S. SNYDER, OF NUTLEY, NEW JERSEY.

BATHER'S CIGARETTE AND MATCH CASE.

Application filed August 28, 1926. Serial No. 131,703.

This invention relates to cigarette and match cases primarily constructed for use by bathers, and has for its main object to provide a case of this character that may be readily attached to the swimming suit belt and to enable cigarettes and matches to be disposed therein and to be fully protected from the water while the bather is within the water.

10 A further object of the invention is to provide a bather's cigarette and match case that is so constructed that when the case is open, the holder for the cigarettes will automatically move outwardly of the case so as to permit the same to be readily removed therefrom.

Other objects and advantages of the invention will become apparent as the nature of the invention is better understood when taken in connection with the accompanying drawing.

In the drawing wherein like numerals indicate like parts:

Figure 1 is a rear side elevation of a bather's cigarette and match case constructed in accordance with the present invention.

Figure 2 is an edge view disclosing the case in open position, a portion of the cigarette holder per se being broken away as to more clearly disclose the means whereby coins may be rigidly attached to said cigarette holder.

Figure 3 is a detail vertical section of the case, and

Figure 4 is a top plan view thereof.

Now having particular reference to the drawing wherein, there is disclosed the most preferred embodiment of the invention with which we are at this time familiar, 5 and 6 designates respectively a pair of case sections of sheet metal, fibre, or other suitable material, that are hingedly interconnected at their bottom sides as at 7. The hinge connection is of the spring type so that said sections automatically move to open position as disclosed in Figure 2 when the same are released. The skirt portion of the section 6 is of greater diameter than the skirt portion of the section 5 in order that said skirt portions will overlap as clearly disclosed in Figures 3 and 4. Within the skirt portion of the section 6 is a rubber ring 8 of the same contour as said skirt portion, said rubber ring being maintained in firm engagement therewith by a metallic ring 9

that may be and preferably is, soldered or welded to the main wall of said section 6. Obviously when the sections are closed, the edge of the skirt of the section 5 will engage said rubber ring 8 so as to provide a water proof joint between the sections.

Upon the top side of the skirt portion of the section 6 is a spring latch lever 10 hooked at its outer end and at its under side for engagement over a lug 11 upon the other case section 5 so as to provide a means for retaining the sections in closed relation against the action of the spring hinge connection 7.

The sections of the case are preferably curved slightly as disclosed in Figure 4 so as to conform to the curvature of the bather's body. The main wall of the section 5 is provided with a pair of loops 12-12 for receiving the strap of the bather's suit, thus permitting the case to be conveniently carried.

Pivots secured upon its opposite ends within the case section 5 at the lower side thereof is a holder 13 of sheet metal or other suitable material, the upper end of which is open for receiving cigarettes 14, the height of this holder being such as to permit the cigarettes to readily move into the case section 5 when it is desired to close said section. Upon the inner face of the main wall of the section 5 is one or more leaf springs 15 that contact the inner side of said holder 13 in order that when the case sections are opened, said holder will be forced outwardly of the case section as disclosed in Figure 2. By reason of such a provision, the cigarettes may be removed from the case when the same is opened.

Within the interior of the case section 6 is a bracket or flexible strip of metal, the same being spot welded or otherwise secured to the section 6. This bracket or strip 16 provides a means to permit the attachment of a pack of matches 17, preferably of the paper type in the case section 6.

The outer wall of the cigarette holder 13 is formed at its upper edge with a plurality of spaced vertically extending depressions 18 for receiving coins as disclosed by the dotted lines in Figure 1 and the full lines in Figure 2. At the lower ends of these depressions the material forming the cigarette holder 13 is so struck outwardly as to provide spring clips 19 in back of which the

coins will engage so as to be firmly retained in proper position upon the holder.

It will thus be seen that we have provided a highly novel, simple, and efficient form of 5 cigarette and match case for bathers, that is well adapted for all the purposes heretofore designated, and even though we have herein shown and described the invention as consisting of certain detail structural ele- 10 ments it is nevertheless to be understood that some changes may be made therein without affecting the spirit and scope of the appended claim.

Having thus described the invention, 15 what we claim is:

In a cigarette and match case for bathers, a pair of hingedly interconnected case sections, means whereby the sections may be se-

cured in closed relation, means whereby the case may be supported upon the suit of the 20 bather, means within one case section for facilitating the attachment of a package of matches therein, a holder for cigarettes pivotally disposed within the other case section, means within the case section for 25 swinging said holder outwardly of the sections when the case is open, the front face of said cigarette holder being provided with coin receiving depressions, and means at the lower ends of the depressions for rigidly 30 securing the coins therein.

In testimony whereof we affix our signatures.

GEORGE H. EYER.
ELWOOD S. SNYDER.
